CLAIM

The ornamental design for a cigarette sheet rolling
device for forming cigarettes, as shown.

DESCRIPTION

FIG. 1 is a top plan view of the cigarette sheet rolling
device for forming cigarettes of the present design with
the bottom plan view being a mirror image of that
shown in this Figure;

FIG. 2 is a right side view of FIG. 1;

FIG. 3 is a left side view of FIG. 1; and,

FIG. 4 is an end view of one end of FIG. 1 with the
other end being a mirror image of that shown in this
Figure.
